Primary Examiner — Katrina N Gonzalez

(57) **CLAIM**

The ornamental design for a dog bathing station, as shown and described.

DESCRIPTION

FIG. 1 is a front perspective view of a dog bathing station showing my new design.

FIG. 2 is a rear perspective view thereof.

FIG. 3 is a bottom perspective view thereof.

FIG. 4 is a front view thereof.

FIG. 5 is a rear view thereof.

FIG. 6 is a left side view thereof.

FIG. 7 is a right side view thereof.

FIG. 8 is a top view thereof.

FIG. 9 is a bottom view thereof.

FIG. 10 is a perspective view of the use state of a dog bathing station.

FIG. 11 is another perspective view of the use state of a dog bathing station; and,

FIG. 12 is another perspective view of the use state of a dog bathing station.

The broken lines illustrate portions of the dog bathing station that form no part of the claimed design.

1 Claim, 12 Drawing Sheets
